(57) **CLAIM**

The ornamental design for a neuromodulator and band set as shown and described.

DESCRIPTION

FIG. 1 is a front-right perspective view of a neuromodulator and band set embodying our new design;

FIG. 2 is a rear-left perspective view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines shown in the drawings illustrate portions of the article which form no part of the claimed design.

1 Claim, 4 Drawing Sheets
